UNITED STATES PATENT OFFICE.

ALBERT LE ROY REUSS, OF BELLEVILLE, ILLINOIS.

INVERTED KEEL.

No. 917,896.

Specification of Letters Patent. Patented April 18, 1909.

Application filed October 12, 1908. Serial No. 457,353.

To all whom it may concern:

Be it known that I, ALBERT LE ROY REUSS, a citizen of the United States, residing at Belleville, in the county of St. Clair 5 and State of Illinois, have invented certain new and useful Improvements in Inverted Keels, of which the following is a specification.

My invention relates to boats, and more 10 particularly to that class of boats known as hunting boats or skiffs.

The invention is directed to the provision of means whereby the boat may glide smoothly over the surface of the water and 15 avoid any possibility of striking logs, stumps, rocks, and other submerged obstructions.

Specifically the invention contemplates the provision of a slot running longitudinally 20 of a boat which not only insures perfect guidance thereof but obviates the disadvantage of any impingement of the keel against obstructions hidden beneath the surface of the water, which difficulty is frequently experienced with the use of the well known 25 types of boats employing projected keels.

To the accomplishment of the recited object and others coördinate therewith, the preferred embodiment of my invention resides in that construction and arrangement of 30 parts hereinafter specified, illustrated in the accompanying drawings, and embraced within the scope of the appended claims.

In said drawings:—Figure I is a bottom plan view of a boat embodying my invention. 35 Fig. II is a central transverse section of the boat. Fig. III is a fragmentary perspective view, partly in section, of one end of the boat. Fig. IV is a top plan view of the boat, and Fig. V is a fragmentary plan view of one 40 extremity of the boat, the top thereof being broken away to more clearly illustrate the features.

Referring more particularly to the drawings for a detail description of my invention, the numeral 5 designates a boat of any 45 preferred construction, the bottom (6) of which is provided with a longitudinally and medially arranged slot (7), the said slot extending entirely through the bottom (6) and 50 through the opposite extremal portions (8) of the boat which are enlarged, as clearly shown in Fig. II of the drawings, to present a suitable thickness for the projecting of the slot. To cover the slot (7) and thus preclude 55 any possibility of the water entering the interior of the boat there is a strip (9) of suit-

able width and length to form a perfect water seal intermediate the portions (8) of the boat, and being superposed and secured to the bottom (6) by nails (10), or other 60 equivalent fastening means. It will be noted that the distal ends of the strip (9) lie contiguous with respect to the inside of the portions (8). At these points I secure blocks (11), the latter being quadrilateral in contour and otherwise generally arranged as to conform with the curvilinear sides of the boat, and at the same time be in juxtaposition to the said end portions (8), the function of these blocks being obviously to reinforce the opposed terminals of the boat and preclude any likelihood of the water finding its way into the boat. To further strengthen the boat, as an entirety, I preferably rabbet the medial portions of the top 70 supports (12) and the ribs (13), as at 14, so that the said supports and ribs may extend transversely of the boat and in this manner impart the maximum amount of rigidity to the structure. It will thus be readily seen 75 that the formation of the slot in the bottom of the boat constitutes an efficient means for directing the course thereof, the advantages of which in overcoming the inherent defects 80 of the ordinary type of boats will be 85 thoroughly understood and appreciated by those skilled in the art.

It should be understood that in its broader aspect my invention comprehends the employment not only of the various means described, but of equivalent means for performing the recited functions.

While the arrangement shown is thought, at the present time, to be preferable, it is desired to reserve the right to effect such 95 modifications and variations thereof as may come fairly within the scope of the appended claims.

Having thus described my invention what I claim is:—

1. A boat having a slot extending through and longitudinally of the bottom thereof, and means for covering the slot on the inside of the boat.
2. A boat having solid portions at each end, a slot running longitudinally and medially of the bottom and solid portions of said boat and extending through said bottom, and means carried by the inside of the boat for covering said slot.
3. A boat having solid portions at each end, a slot running longitudinally and me-

dially of the bottom and solid portions of said boat and extending through said bottom, and a strip arranged intermediate said solid portions and adapted to cover the slot in the bottom.

4. A boat having solid portions at each end, a slot running longitudinally and medially of the bottom and solid portions of said boat and extending through said bottom, a strip arranged intermediate said solid

portions and adapted to cover the slot in the bottom, and blocks secured on the terminals of said strips and lying contiguous said solid portions and the sides of the boat.

In testimony whereof I affix my signature, 1
in presence of two witnesses.

A. LE ROY REUSS.
